UNITED STATES PATENT OFFICE.

MATTHEW F. BRAMLEY, OF CLEVELAND, OHIO.

LANTERN CAGE.

Application filed March 25, 1922. Serial No. 546,620.

To all whom it may concern:

Be it known that I, MATTHEW F. BRAMLEY, a citizen of the United States, residing at 11400 Harbor View Drive, Cleveland, in the State of Ohio and Cuyahoga County, have invented a new and useful Improvement in Lantern Cages, of which the following is a specification, the principle of the invention being herein explained and the best mode in which I have contemplated applying that principle, so as to distinguish it from other inventions.

My invention pertains to a lantern cage or safety cage for signal lights.

The object of my invention is to provide a safety cage which, with consideration of the insurance it will afford, will be of inconsiderable cost. As herein disclosed, the construction is of a size and weight which will more conspicuously display the light signal and more firmly hold it in place respectively. I propose to have the construction embodying my invention portable and have it include a reticulated cage in which a lantern is to be detachably suspended and which is provided with a door through which the lantern may be inserted or withdrawn together with means for locking the door. Moreover, the shape of the cage in its entirety is so designed as to facilitate stacking and hauling of a plurality of structures in a compact relationship.

Adverting to the drawings:

Figure I is a front elevation of a lantern cage embodying my invention.

Figure II is a top plan view of Figure I.

Figure III is mainly a vertical section on line III—III of Figure II, the lantern being omitted.

Figure IV is a horizontal section on line IV—IV of Figure I.

Figure V is a partial section of the upper end of my cage showing a suspension hook tilted aside to permit positioning of a lantern ball.

Figure VI is a front elevation of a modified form of cage.

Figure VII is a top plan view of the top of Figure VI.

Figure VIII is a horizontal section on line VIII—VIII of Figure VI.

Figure IX is a front elevation of a second modification.

Figure X is a top plan view of Figure IX.

Figure XI is a horizontal section on line XI—XI of Figure IX.

The preferred form of my lantern cage includes a base 1 which is to be considered as supplying adequate weight to hold the remainder of the structure in an upright position. If desired convenient additional weighting means (not shown) may be placed upon the base 1. Attached to four corners of the base 1 are standards 2 shown as angle irons which converge in an upward direction to be held together at the top by a square angle iron frame 3 and a top surface 4. The structure described will be seen to be of pyramidal form which is more likely to resist tipping upon the base 1 and incidentally reduces the space required in stacking or hauling a plurality of cages, as will be readily understood.

Loosely inserted through a hole 5 in the center of the top 4 is the shank 6 of a hook having its bight 7 suspended interiorly and provided exteriorly with a looped handle 8. The fitting of the hook is such that it may be readily tilted to one side as shown in Figure V to afford clearance for a purpose to be hereinafter explained. Between the base 1 and top 4, somewhat nearer the bottom than the top, the standards 2 are stiffened by an enclosing frame 9. A reticulated wire cage is fitted around the standards 2 between the top 4 and the frame 9, the wire net work of the cage 10 enabling the emergence of light rays. Pivoted at 11 across two of the standards 2 is a bottom door frame 12 carrying a screen 13 and a cross brace 14 with its end perforated as clearly shown in Figure IV. The two standards on the opposite sides from those which carry the pivot 11 carry an angle iron 15 fashioned with a hole 16 with which the hole in the brace 14 is adapted to register when the bottom or door 12 is swung up to its closed position, so as to enable attachment of a padlock 17 shown in Figure I. A lantern 18 is to be suspended by engagement of its bail 19 in the bight 7 of the hook, so as to swing freely while protected by the wire cage 10. Manifestly, the construction of the lighting means is of no consequence except that it be adapted for detachable connection so as to enable its withdrawal when the door 12 is opened.

The modification shown in Figures VI to VIII inclusive shows a wire cage including four standards 20 with their lower ends 21 bent to form bases. The standards are held in position by a continuous length of

wire 22 wound thereabout after the manner of an advancing spiral. The structure includes top braces 23 which cross each other and support a suspension device 24 for the lantern. A cage closing structure 25 is hinged at 26, and adapted to be secured at a point 27 on the opposite side by means of a padlock 28.

The modification shown in Figures IX to XI illustrates a tripod cage including three legs 29 secured by a frame 30 intermediately of their ends. Just below the frame 30 is a triangular structure 31 including a brace 32 provided with a fork 33 which has opposed apertures adapted to register with a hole through one of the legs 29 to enable insertion therethrough of the loop 34 of a padlock 35. The tops of the three legs 29 are held together by a cap 36 through the middle of which a hook 37 extends purposed to support a lantern 38. Wire net work 39 is then attached in any feasible manner so as to enclose the compartment between the structure 31 and the tops 36. It is to be understood that the bottom of the lantern preferably swings clear of the structure 31, past which it may be withdrawn when the lock is removed and the brace 32 swung downwardly.

30 I claim:—

1. The combination of a base, standards

carried by said base, a reticulated cage carried by said standards, a door between the top of said standards and the lower end of said cage adapted to close the latter, and a lighting device in said cage. 35

2. A device of the character described comprising a portable pedestal, a cage carried by said pedestal, suspension means loosely carried by the top of said cage, a door for said cage, a lamp insertable past said door and provided with means for engaging said suspension means and a lock for said door. 40

3. A safety cage comprising the combination of a reticulated cage, a lantern in said cage, a perforate angle iron carried by said cage, a door fashioned with a perforate cross brace, said openings in said angle iron and door adapted to register, and 45 a lock insertable through said openings. 50

4. The combination of a support flared in a downward direction, a reticulated cage carried in an elevated position by said support, a door dividing said support and cage, a hook loosely carried by the top of said cage, and a lantern suspended from said hook and a lock for said door. 55

Signed by me, this 23rd day of February, 1922.

MATTHEW F. BRAMLEY.
